(74) *Attorney, Agent, or Firm*—Jeffer Mangels Butler & Mitchell LLP(57) **CLAIM**

The ornamental design for a novelty video insert, as shown and described.

DESCRIPTION

FIG. 1 is a perspective view of the novelty video insert showing our new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a top elevational view thereof; and,

FIG. 7 is a bottom elevational view thereof.

The broken lines shown on FIGS. 1, 2 and 5 form no part of the claimed design.
